UNITED STATES PATENT OFFICE.

GEORGE D. R. AIKIN, OF LOUISVILLE, KENTUCKY.

PRACTICE-CARTRIDGE.

SPECIFICATION forming part of Letters Patent No. 517,719, dated April 3, 1894.

Application filed August 19, 1893. Serial No. 483,504. (No model.)

To all whom it may concern:

Be it known that I, GEORGE D. R. AIKIN, a citizen of the United States, and a resident of Louisville, in the county of Jefferson and State of Kentucky, have invented certain new and useful Improvements in Cartridges; and I do declare the following to be a full, clear, and exact description of the invention, such as will enable others skilled in the art to which it appertains to make and use the same, reference being had to the accompanying drawings, and to letters marked thereon, which form a part of this specification.

Figure 1 is an enlarged view of cartridge. Fig. 2 is a similar view in section. Fig. 3 is a similar view of modification, in section.

This invention has relation to certain new and useful improvements in cartridges, and it consists in the novel construction and combination of parts, all as hereinafter described, and pointed out in the appended claim.

It is the object of the invention to provide a cartridge especially designed for light shooting, gallery practice, &c., and carrying light charges of explosive material, which, while having but a small chamber to receive the charge, will at the same time possess all the advantages of a long cartridge; and the invention is designed to be applied to all forms of rifle cartridges, both center and rim fire, of paper, metal, or composition, and of all calibers.

In carrying out my invention I make the cartridges their full usual length and of the ordinary exterior form, but instead of being

chambered their full depth in the ordinary manner, the cartridge is made solid from the base for a considerable portion of its length as shown at A with the exception of a small bore a, communicating with the cap seat or 40 cap tube. By this construction it will be seen that the chamber B for the charge is made shallow, and it is intended to make the solid portion of greater or less extent so that cartridges may be provided with charges varying 45 from three-fourths to one-tenth of the usual charge. The bottom of the chamber B is preferably made concave. The solid portion of the cartridge may be cast or formed integral with the shell or the base in the process 50 of manufacture.

Having thus described my invention, what I believe to be new, and desire to secure by Letters Patent, is—

As a new article of manufacture, a cartridge 55 shell or blank of the usual length, and formed of a single piece of metal, the internal solid portion thereof extending a portion of its length, whereby the explosive chamber of the shell or blank is reduced in length, and a 60 small longitudinal bore or passage through said solid internal portion and communicating with the cap or anvil seat, substantially as specified.

In testimony whereof I affix my signature in 65 presence of two witnesses.

GEO. D. R. AIKIN.
